VARIABLE PITCH SCREW PROPELLER

Ettore Lanzerotti-Spina, deceased, late of Pre-
bend Gardens, Stamford Brook, London, Eng-
land, by Amelia Ann Lanzerotti-Spina, execu-
trix, London, England

Application June 30, 1932, Serial No. 620,271
In Great Britain July 7, 1931

7 Claims. (Cl. 170—163)

This invention relates to variable pitch pro-
pellers which employ for pitch adjustment a non-
reversible or self-locking mechanism comprising
a non-rotatable sliding sleeve co-axial with the
propeller blade having both steep and shallow
screw threads which engage with corresponding
threads upon the root of the propeller blade and
upon a rotatable sleeve respectively, the blade
and sleeve being prevented from moving longi-
tudinally.

In constructions of this kind heretofore de-
vised the propeller blades have been driven, and
the centrifugal forces upon them resisted, by
cylindrical extensions of a hub on the propeller
15 shaft, within which extensions the blade roots are
received; though further support has been af-
forded by a spider or trunnioned sleeve, the arms
or trunnions of which enter the blade roots. To
these same hub extensions the non-rotatable
20 sliding threaded sleeve has been splined, the
threaded root of the blade lying within that sleeve
and the threaded rotatable sleeve surround-
ing it.

It is the purpose of the present invention to
25 improve the construction of this class of variable
pitch propeller with a view to reducing its weight,
reducing the overhang of the propeller beyond
the adjacent propeller shaft bearing, and reduc-
ing the diameter of the hub structure, and to
30 these ends to make the pitch adjusting mecha-
nism more compact, while also rendering it read-
ily accessible.

With this purpose in view the invention con-
35 templates utilizing the trunnion within the blade
root for other functions than it has hitherto
served; and a principal part of it consists in
modifying the construction of the trunnion to
enable it to perform these additional functions,
40 and in modifications of the rest of the structure
which are thereby rendered necessary and possi-
ble.

In particular the invention designs to employ
the trunnion for holding the sliding pitch ad-
45 justing sleeve against rotation, and thereby re-
lieving the hub structure of this function. A
more important step is to transfer to the trun-
nion the function of transmitting driving torque
to the propeller blade and of withstanding cen-
50 trifugal forces. This involves considerable
strengthening and enlargement of the trunnion,
but as there is space for this within the propeller
root no increase in the total bulk of the struc-
ture is involved; on the contrary the hub struc-
55 ture can now be reduced in size and simplified

so that a saving of weight is achieved and the
overhang of the propeller is reduced.

It will be understood that by "trunnion" is
here meant a radial projection from the pro-
peller axis of circular cross-section and of robust
construction appropriate to its functions; in the
common case of a propeller with two blades the
analogy with the trunnions of a gun is obvious.

Further features of the invention will appear
from the following description of constructions
embodying it which are illustrated in the ac-
companying drawings.

In these drawings,

Figure 1 is a part section and part end eleva-
tion of the centre of a propeller showing the
mounting of the blade and the provision for ad-
justing its pitch;

Figure 2 is a section on the line II—II of
Figure 1;

Figure 3 is a half axial section through an
alternative construction, and

Figure 4 is a part transverse section of it;

Figure 5 is a diagrammatic axial section
through the shaft only illustrating a modified
means of actuating the pitch adjusting mecha-
nism.

In Figures 1 and 2 the trunnions 1 are cylin-
drical or tapered radial projections from a sleeve
2 integral with them and splined to the propeller
shaft. The sliding pitch adjusting sleeve 3 is
splined upon this trunnion. It is equipped with
both steep and shallow screw threads 4 and 5
respectively. These are shown as both external
threads, this arrangement being most economical
of space and weight. With the steep pitch thread
4 there engages a correspondingly threaded mem-
ber 6 forming part of or attached to a blade root
mounting 7. This mounting has a conical skirt 8
upon which the root 9 of the propeller blade is
seated and keyed; if preferred, however, the seat-
ing may be upon a cylindrical surface. The blade
root is secured on the blade root mounting by
the flanged ring 10 engaging the sleeve and screw-
ing upon the blade root.

A thrust and journal bearing shown as a ball
bearing 11 is interposed between the blade root
mounting 7 and the trunnion 1 near their outer
ends. One race 12 of the bearing rests upon a
shoulder on the blade root sleeve while the other
13 is retained by a collar 14 screwing upon the
trunnion. The races may be concentric and
deeply recessed so that the bearing can take
thrust in shear; but in the construction illus-
trated the one race is radially beyond the other
so that the bearing takes centrifugal forces in

compression. A short cylinder 15 serving as a distance piece rests upon the race 12, surrounds the race 13 and forms an abutment for a locating washer 16 which extends over the race 13 and is pressed on the distance piece 15 by a ring 17 screwing into the end of the blade root sleeve. A similar ring 18 secures a protecting cap 19.

With the shallow pitch thread 5 upon the sliding sleeve 3 there engages a similarly threaded 10 rotary pitch adjusting sleeve 20, carried in ball and roller bearings 21 in the blade root sleeve. The rotary sleeve 20 extends inward beyond the sliding sleeve 3 and a roller or other bearing 22 is interposed between it and the trunnion to complete the journal guidance of the blade. On the lower edge of the rotary sleeve 20 are bevel teeth 23.

The rotary pitch adjusting sleeves 20 are shown as operated through the medium of bevel segments 24 mounted on stud shafts 25 projecting from the sleeve 2 at right angles to the trunnions. These segments may be turned by any convenient means. The drawings show them equipped with spur teeth 26 with which engage racks 27 mounted 20 to slide parallel with the propeller shaft in a casing member 28 embracing the shaft and the roots of the blades. These racks, together with dummy sliding rods 29, support a grooved ring 30 engaged by a control fork 31 in well known manner.

When it is desired to vary the pitch of the propeller blades the grooved ring 30 is shifted one way or the other by means of the control fork 31; the racks 27 engaging spur teeth 26 turn the bevel segments 24 and through them the rotary sleeves 20. Since the ball bearing 21 prevents sleeve 20 moving endwise, and since the sleeve is screwed upon the shallow thread 5 of the sliding pitch-adjusting sleeve 3 which is prevented from turning by its splined engagement with the trunnion 1, rotation of the sleeves 20 causes the sliding sleeves 3 to move inward or outward as the case may be. But the steep pitch thread 4 of each sleeve 3 engages the correspondingly threaded member 6 40 upon the blade root sleeve 7; hence inward or outward movement of the non-rotating sleeves 3 causes the members 6 and therefore the blades to turn. This pitch-adjusting mechanism is self-locking, for torque upon the blades communicated 50 to the members 6 cannot turn the sleeves 3 since they are splined upon the trunnion 1; nor can it shift the sleeves inward or outward both because the threads 4 are steep and because the threads 5 are shallow.

55 The modified construction shown in Figures 3 and 4 differs from that just described chiefly in the fact that the thrust bearing 32 interposed between the blade root and the trunnion 1 is at the base of the trunnion. This makes possible some saving of weight in the outer part of the trunnion. A consequence of this change is that the rotary pitch adjusting sleeve 20 is now radially outside the steep pitch threaded member 6 attached to the blade root mounting 7. To operate this rotary sleeve a spindle 33 is carried through the trunnion. It is supported by bearings in the trunnion and attached by the member 34 to the sleeve. Journal bearings 35 are interposed between the member 34 and the trunnion 1, and between the member 34 and the blade root sleeve to complete the journal guidance of the latter. The guidance of the rotary sleeve 20 is completed by the bearing 36. The spindle 33 has bevel teeth 37 at its lower end, engaging a bevel pinion 38 supported within the sleeve 2. This

pinion is turned by pinions 39 actuated through rack 27 and spur teeth 26.

The actuating mechanism here illustrated further differs from that previously described in that it is carried through the propeller shaft. A rod or tube 40 extending through the shaft may be moved longitudinally by the non-rotating part of the actuating mechanism (e. g. a lever replacing fork 31), and communicates this movement to a shell 41 rotatably supported on it. An arm 42 upon the shell 41 is joined by 43 to the rack 27. In Figure 3, arm 42 and connector 43 have been turned out of their proper position into the plane of the section to show their structure.

The pitch adjusting mechanism may be controlled by hand or automatically, for instance by connection to a centrifugal governor driven by the engine. In either case the connection between the control handle or device and the pitch-adjusting mechanism may be mechanical, as in the cases above described, or hydraulic. An example of a hydraulic connection between the non-rotating and rotating parts of the actuating mechanism is illustrated diagrammatically in Figure 5. A part of the hollow propeller shaft 44 is utilized as a cylinder 45 for a piston 46 the piston rod 47 of which replaces the member 40 of Figure 3. It is shown as joined by a link directly to the bevel segments 24; ring conduits 49 and pipes 50 convey the fluid by which the device is operated.

It is claimed:

1. In a variable pitch propeller the combination of a propeller shaft, blades rotatably mounted thereon, a trunnion for each blade entering the blade root and driven by the propeller shaft, a sleeve slidable radially upon said trunnion and prevented from rotation thereon having both steep and shallow screw threads, a steep threaded member on the blade root engaged with said steep thread, a shallow threaded rotatable sleeve engaged with said shallow thread, and means for turning said sleeve.

2. In a variable pitch propeller the combination of a propeller shaft, blades, a trunnion for each blade capable of driving the blade, said trunnion being driven by the propeller shaft and entering the blade root, means for transmitting the radial stress on the blade to the trunnion and for affording the blade journal support from the trunnion at points a substantial distance apart, a sleeve with both steep and shallow threads slidable but not rotatable upon said trunnion its steep thread engaging a corresponding thread upon the blade root, a rotatable sleeve held against axial movement having a shallow thread engaging the shallow thread of the slidable sleeve, and means for turning said rotatable sleeve.

3. In a variable pitch propeller the combination of a propeller shaft, blades, a trunnion for each blade capable of driving the blade, said trunnion being driven by the propeller shaft and entering the blade root, a thrust bearing interposed between the blade root and the trunnion at the inner end of the trunnion to transmit to the trunnion the radial stress on the blade, a journal bearing between the blade root and trunnion at the outer end of the trunnion, a sleeve with both steep and shallow threads slidable but not rotatable upon said trunnion its steep thread engaging a corresponding thread upon the blade root, a rotatable sleeve held against axial movement having a shallow thread engaging the shallow thread

- of the slidable sleeve, and means for turning said rotatable sleeve. 80
4. In a variable pitch propeller the combination of a propeller shaft, blades rotatably mounted thereon, a trunnion for each blade entering the blade root and driven by the propeller shaft, a sleeve slidably radially upon said trunnion and prevented from rotation thereon having both steep and shallow screw threads on its outer surface, a steep threaded member on the blade root engaged with said steep thread, a shallow threaded rotatable sleeve engaged with said shallow thread, and means for turning said sleeve. 85
5. In a variable pitch propeller the combination with a hollow propeller shaft and blades of a radially sliding non-rotatable sleeve for each blade having both steep and shallow screw threads, a threaded member on the blade root engaging the steep thread of said sliding sleeve, a rotatable sleeve held against radial movement having a shallow thread engaging the shallow thread of said sliding sleeve, and means including a member passing through the hollow propeller shaft for turning said rotatable sleeve. 90
- 25 6. In a variable pitch propeller the combination of a propeller shaft, blades, a hollow trunnion for each blade capable of driving the blade, said trunnion being driven by the propeller shaft and entering the blade root, a thrust bearing interposed between the blade root and the trunnion at the inner end of the trunnion to transmit to the trunnion the radial stress on the blade, a 95
- journal bearing between blade root and trunnion at the outer end of the trunnion, a sleeve with both steep and shallow threads slidable but not rotatable upon said trunnion its steep thread engaging a corresponding thread upon the blade root, a rotatable sleeve held against axial movement having a shallow thread engaging the shallow thread of the slidable sleeve, a spindle fastened to said rotatable sleeve extending through the trunnion, and means for turning said spindle. 100
7. In a variable pitch propeller the combination of a hollow propeller shaft, blades, a trunnion for each blade capable of driving the blade, said trunnion being driven by the propeller shaft and entering the blade root, means for transmitting the radial stress on the blade to the trunnion and for affording the blade journal support from the trunnion at points a substantial distance apart, a sleeve with both steep and shallow threads slidable but not rotatable upon said trunnion its steep thread engaging a corresponding thread upon the blade root, a rotatable sleeve held against axial movement having a shallow thread engaging the shallow thread of the slidable sleeve, and mechanism for turning said rotatable sleeve including hydraulic means for conveying motion from the non-rotating part of said mechanism to its rotating part. 105
